UNITED STATES PATENT OFFICE.

CHARLES B. MOORE, OF EVANSTON, ILLINOIS, ASSIGNOR, BY MESNE ASSIGNMENTS, TO AMERICAN ARCH COMPANY, OF NEW YORK, N. Y., A CORPORATION OF DELAWARE.

LOCOMOTIVE-BOILER FURNACE.

1,138,047.

Specification of Letters Patent.

Patented May 4, 1915.

Application filed December 18, 1911. Serial No. 666,343.

To all whom it may concern:

Be it known that I, CHARLES B. MOORE, a citizen of the United States, and a resident of the city of Evanston, county of Cook, 5 and State of Illinois, have invented certain new and useful Improvements in Locomotive-Boiler Furnaces, of which the following is a specification.

My invention relates to improvements in 10 locomotive boiler furnaces and has special reference to improvements in refractory baffles or deflecting walls, commonly called arches, for the fireboxes of locomotive boilers.

15 The general objects of my invention are to provide an improved refractory arch which may be easily and quickly installed in locomotive fireboxes; to provide an arch which shall be of comparatively light weight 20 and low cost; to provide an arch which shall be adapted for easy repair and parts of which can be removed to afford easy access to the firebox sides and flue sheet; and to provide an arch of a form that will materially assist in admixing and igniting the 25 firebox gases and other combustibles.

A special object of my invention is to provide an improved arch of the character here outlined which shall be adapted for use in 30 locomotive fireboxes that are equipped with arch supporting tubes, the arch itself being so constructed, formed and proportioned, that the unequal abrasive action to which arches of this character are subjected in 35 their different parts is compensated for and, consequently the arches are of substantially equal life throughout their extent.

My invention consists in the several improvements, the various constructions and 40 the combinations of parts by which these objects are attained, together with others appearing herein and all as hereinafter fully described and particularly pointed out in the appended claims.

45 My invention will be more readily understood by reference to the accompanying drawings, forming a part of this specification, and in which:

Figure 1 is a central vertical longitudinal section of a locomotive boiler firebox 50 equipped with a refractory arch embodying my invention; Fig. 2 is a horizontal section of the firebox on the line 2-2 of Fig. 1; Fig. 3 is a vertical transverse section of the firebox on the line 3-3 of Fig. 1; Figs.

4 and 5 are detail transverse sections of the arch on lines 4-4 and 5-5 respectively of Fig. 1; and Fig. 6 is a view in perspective of one of the arch panel or cover bricks.

My invention may be embodied in arches 60 of varying details of construction and occupying different positions in the firebox and although I have herein confined the illustration of the invention to so-called refractory front arches which extend from 65 side to side in the firebox and practically abut the firebox flue sheet, I desire that it shall be understood that my invention is not confined or limited to this specific form of arch.

70 A locomotive boiler firebox, as illustrated in the drawings, is made up of a flue sheet 2, side sheets 3-3, a rear sheet 4 and a crown sheet 5. The firebox is equipped as usual with a grate 6, the flues 7 lead forward from 75 the flue sheet and the rear sheet is provided with a fuel door or opening 8. The firebox shown in the drawings is equipped with a pair of circulating tubes 9, the same extending upwardly and rearwardly from 80 the lower part of the flue sheet to the upper part of the rear sheet and serving to increase the circulation of water between the front and rear water legs of the boiler. These tubes 9 extend substantially parallel 85 with the side sheets 3 and are comparatively widely separated.

75 A so-called front arch usually occupies an inclined position in the forward end of the firebox extending from side sheet to side 90 sheet, its lower end being in abutment with or close to the flue sheet. The function of such arches is to deflect the firebox gases out of the direct path from the grate to the flues and cause them not only to be retained 95 in the firebox a longer time than would otherwise occur, but also to pass or flow backward and forward through the firebox and thus distribute the heat of the burning gases to the whole interior surface of 100 the firebox and especially throughout the whole length of the crown sheet. Arches of this character, especially where they are made of comparatively thin members, quickly attain the maximum temperature of 105 the firebox and thereby assist in the ignition of the firebox gases and other combustibles. The arch being in the path of the rising gases is effective to return to the fuel bed, the cinders and the solid fuel particles 110

which are carried upward by the strong artificial draft usually employed in locomotives. An incidental effect of this function of arches of this character is that the arches are abraded, scoured or worn away by the impact of the cinders and fuel particles on its under surface. This abrasive action is more severe upon some parts of the arch than upon others, and a particular feature of my invention is to provide an arch structure varied in thickness in its various parts for the purpose of providing against this unequal abrasive or scouring action whereby the arch is of substantially equal life throughout its extent. In other words, my object is to provide an arch structure which will better perform the main functions of arches of this character in deflecting, commingling, admixing and igniting the firebox gases and which will in a practical sense prevent one part of the arch from wearing out in advance of another part. To this end I build my arches of a number of refractory parts so disposed or arranged as to present a large superficial area or igniting surface composed of portions which are inclined at various angles to each other and the arch body itself being reinforced, thickened or proportioned in thickness to the abrasive action to which it is subjected in use. In carrying out my invention I employ a considerable number of independent bricks usually of several different forms or shapes and assemble them in a way to secure these advantages and others herein mentioned. A special feature of my invention resides in an inclined front arch built or composed of two kinds or forms of brick, that is, supporting and panel bricks. The supporting bricks are supported by the tubes 9 and are arranged in pairs, resting at their lower ends upon and against said tubes and abutting at their upper ends substantially midway between the tubes, thereby forming refractory self-supporting spans or arches between the tubes. I provide two or more of these self supporting spans spaced apart upon the tubes and retain them in spaced relation by means of the cover or panel bricks which rest upon and extend between adjacent spans and practically and substantially close the openings between them. The various bricks of the arch are limited in size by the features that they should be light enough to be readily handled and placed in position and should be small enough to be readily passed through the fire door or opening 8. It is desirable, however, that they be as large as these features will permit to the end that as few as possible of the individual bricks will be necessary to build the arch. The size of the supporting bricks is determined by their length and the weight of the arch, these bricks sustaining not only their own weight but the weight of the panel

or cover bricks as well. I prefer to make these bricks substantially as wide as they are thick and they are of necessity made long enough so that a pair of them will properly span the tubes. The panel or cover bricks, however, not having to sustain any weight, except their own, can be made both thin and light and I prefer to make them as light as possible so that the arch as a whole will not be too heavy to be sustained safely upon the tubes.

Being made up of small units my arches can be readily and quickly installed with a minimum expenditure of time and labor. Another inherent feature in my improved arches is that they are in a practical sense flexible, that is, being formed of individual members, the joints between which are overlapped and protected against the cementing action of the slag which is formed upon such arches, they do not become rigid after the manner of solid arches but remain sufficiently flexible to readily adjust themselves to slight changes in the dimensions or shape of the firebox due to variations in temperature and pressure. These several features are preserved in the arch, as illustrated in the drawings, which consists of several supporting spans, each formed of two span bricks *a* which are provided on their lower ends with sockets or grooves *a'* adapting them to rest against and upon the tubes 9, and at their upper ends with complementary interlocking tongues *a*² and grooves *a'*² whereby the abutting ends are prevented from relative longitudinal and vertical movement once they have been positioned. These spans are spaced apart upon the tubes at different heights and are retained in spaced relation by the cover or panel bricks *b*. The panel bricks *b* are preferably interposed between the upper edges of the supporting bricks *a*, which are provided with grooves or gains *a*⁴ to receive the flange *b'* of the bricks *b*. It will now be seen that irrespective of the shape or contour of the upper surface of the arch, the lower or under surface presents a plurality of gas deflecting cavities, pockets and walls arranged at various angles and having different dimensions. The cover or panel bricks *b*, being arranged between the upper edges of the supporting bricks, are protected to some extent from the scouring or abrasive action of the cinders or fuel particles carried upward by the firebox gases, but as the gases, on account of their deflection by the arch, flow upwardly along the under surface of the arch, the upper ends of the cover or panel bricks are exposed to a much heavier or greater abrasive action than the lower ends and for this reason I thicker or reinforce the upper ends *b*² of the cover bricks *b*, as shown in the drawings, to provide against this excessive wear. The added

thickness of the cover bricks b provides them with depending shoulders b^e at their upper ends which abut the lower side face of the supporting bricks and aids in retaining the supporting bricks in position. This formation of the panel bricks provides one end of them with a socket or groove b^e and to complete the arch I place a number of these panel or cover bricks between the tubes 10 and respective side sheets of the firebox, placing the socketed ends of these bricks upon the tubes and leaning the bricks in inclined position against the side sheets. The arch as thus constructed is formed of 15 but two forms or patterns of bricks, consequently, the arch is an economical one to install and maintain for the reason that it is necessary to carry but these two forms of brick in stock at convenient points, and an 20 arch constructed as herein defined may properly be termed a two-brick arch in that but two forms or patterns of brick are used in its construction. The bricks a being comparatively long and consequently quite 25 heavy, I preferably lighten them to as great an extent as possible by providing them with cavities a^e upon their under surfaces. These cavities extend substantially the whole length of the bricks and provide them with 30 comparatively thin marginal edges a^e and thus not only reduce the weight of the bricks but the cavities add to the efficiency of the arch in its function of admixing the firebox gases while the thin margin of edges aid in 35 the ignition thereof. And further, I preferably make these supporting bricks tapered in thickness from their upper to their lower ends, first to decrease their weight as much as possible and second for the purpose of 40 making them thicker at their upper ends where they are naturally exposed to the greatest abrasive wear.

In installing my improved arches in locomotive fire-boxes, I place a pair of the span 45 bricks upon the lower ends of the tubes 9 and in abutment with the flue sheet, interlocking their abutting ends together. As they rest upon the tubes 9, which are inclined to the flue sheet, their lower ends are 50 spaced from the flue sheet and I retain their lower ends thus spaced by means of spacing blocks or bricks c which are formed to conform on their lower sides to the tubes upon which they rest and are retained in position 55 between the arch and the flue sheet by the weight of the arch which rests against them. The openings or spaces thus formed between the lower end of the arch and the flue sheet serve to permit the cinders which 60 fall upon the back of the arch to return to the fuel bed. Having the first span in position I place a similar span parallel with the first and higher up on the tubes and retain it in position by means of a number of the 65 cover or panel bricks b which I place be-

tween the two spans. As illustrated, I prefer to use two of the cover bricks between each two adjacent supporting bricks. As shown in Fig. 5, the cover bricks depend between the supporting bricks and they are 70 retained in position transversely of the firebox by the tubes 9 against which the lowermost of said cover bricks rest. The main or central portion of the arch is completed by adding further spans and rows of spacing 75 or cover bricks to build the arch of the desired length or height. Usually the arch extends rearwardly to about the center of the firebox, although in some instances it might consist of but two parallel spans and 80 an intermediate row of the cover bricks. I complete the arch as a whole by filling in between the side edges of the center portion of the arch and the side sheets by placing a 85 number of the panel or cover bricks b in position upon the tubes 9 and resting against the side sheets 3. These side bricks not only complete the arch but in a practical sense lock the whole arch against lateral movement in the firebox as they are preferably 90 of such a length that they wedgingly rest or engage the tubes and the side sheets upon which they are supported.

It will now be understood that a front arch as herein defined comprises a plurality of 95 leaves or panels arranged longitudinally in the firebox, resting at one edge upon a circulating tube and leaning either against a similar leaf or panel or against the adjacent side sheet of the firebox. An arch of this 100 character provides a plurality of sections or portions which I have termed leaves and which are arranged in planes disposed at different angles in relation to the side sheets of the firebox and each of these leaves or 105 panels is composed of individual bricks which are characterized by being thicker at one end than at the other, whereby the parts of these leaves or panels which are exposed to the most excessive wearing effect of the 110 cinders are reinforced or thickened.

As many modifications of my invention will readily suggest themselves to those skilled in the art, I do not limit my invention to the specific structures herein shown 115 and described.

Having thus described my invention I claim as new and desire to secure by Letters Patent:—

1. A locomotive boiler firebox containing 120 two circulating tubes, in combination with a refractory front arch therein extending from side to side and in abutment with the flue sheet composed of two forms of bricks and comprising a plurality of two-brick 125 spans spaced apart on the tubes, the bricks of the spans being all of the same form and thickest at their upper ends, an alternate series of filling or panel bricks arranged between said spans spacing them apart and 130

filling the openings between them, the upper end of said panels also being thicker than their lower ends, and a series of bricks identical with said panel bricks arranged between each tube and the adjacent side sheet and serving to complete the arch, substantially as described.

2. A locomotive boiler firebox containing two comparatively widely separated, substantially parallel inclined circulating tubes, in combination with a "two-brick" refractory front arch comprising a plurality of parallel, self-supporting spans, each composed of two identical, tapered supporting bricks, their thinner ends resting upon and against respective tubes, and their thicker ends abutting each other in interlocked en-

gagement, said spans being spaced apart upon the tubes, a plurality of identical tapered panel bricks arranged between and spacing said spans, and a plurality of similar tapered panel or filling bricks arranged in each side of the firebox resting on and against a tube and wedgingly engaging the respective side sheet, substantially as described.

In testimony whereof, I have hereunto set my hand, this 5th day of December, 1911, in the presence of two subscribing witnesses.

CHARLES B. MOORE.
